FURNITURE DRAWER FRONT OR THE LIKE

Richard M. Chapin, 2200 Pinewood Circle,
Charlotte, N.C. 28211

Filed Jan. 2, 1973, Ser. No. 320,513

Term of patent 7 years

Int. Cl. D6—06

U.S. Cl. D6—193

FIG. 1 is a front elevational view of a furniture drawer front showing my new design;

FIG. 2 is an enlarged vertical sectional view taken along line 2—2 in FIG. 1;

FIG. 3 is an enlarged vertical sectional view taken along line 3—3 in FIG. 1; and

FIG. 4 is a fragmentary enlarged horizontal sectional view taken along line 4—4 in FIG. 1.

The back of the furniture drawer front shown is substantially plain and unornamented.

I claim:

The ornamental design for a furniture drawer front or the like, substantially as shown and described.
